(57) **CLAIM**

The ornamental design for a vehicle mattress as shown and described.

DESCRIPTION

FIG. 1 is a perspective view of a vehicle mattress according to the present invention.

FIG. 2 is a front view of the invention shown in FIG. 1.

FIG. 3 is a rear view of the invention shown in FIG. 1.

FIG. 4 is a side view of the invention shown in FIG. 1.

FIG. 5 is a second side view of the invention shown in FIG. 1.

FIG. 6 is a top view of the invention shown in FIG. 1; and, FIG. 7 is another perspective view thereof, showing the vehicle mattress as used in a vehicle.

The broken lines shown in FIGS. 1-7 are for the purpose of illustrating portions of the vehicle mattress and form no part of the claimed design. The broken lines shown in FIG. 7 depict the environment of a vehicle which form no part of the claimed design.

1 Claim, 7 Drawing Sheets
